HOLDER FOR BRUSH ELEMENT OR ELEMENTS

Willis Z. West, Jr., and Morgan F. Gamble,
Winston-Salem, N. C.

Application March 6, 1952, Serial No. 275,162

6 Claims. (Cl. 310—244)

1

Our invention relates to holders for brush elements of rotary switches or the like.

An important object of the invention is to provide a holder of the above-mentioned character, of simplified construction and which is supported independently of a rotary switch in connection with which it is used.

A further object of the invention is to provide a holder for brush elements which will render it easy to remove and replace the brush elements.

A further object of the invention is to provide a holder including torsional coil springs to yieldingly press the brush elements into contact with coacting parts.

A further object of the invention is to provide a holder which is strong, durable, compact and inexpensive to manufacture.

This application is a continuation in part of our co-pending application for Centrifugal Switch, Serial Number 123,880, filed October 27, 1949, now Patent No. 2,595,621.

In the accompanying drawings, forming a part of this application, and in which like numerals are employed to designate like parts throughout same,

Figure 1 is a side elevation of a centrifugal switch having a brush holder embodying our invention connected therewith,

Figure 2 is an exploded perspective view of the brush holder,

Figure 3 is a plan view of the brush holder and switch,

Figure 4 is a longitudinal section taken on line 4—4 of Figure 1,

Figure 5 is an enlarged horizontal section taken on line 5—5 of Figure 1,

Figure 6 is a side elevation of a second form of brush holder embodying our invention and the rotary switch,

Figure 7 is a plan view of the same,

Figure 8 is a vertical section taken on line 8—8 of Figure 6,

Figure 9 is a vertical section taken on line 9—9 of Figure 8,

Figure 10 is an exploded perspective view of the brush holder,

Figure 11 is a side elevation of a brush holder embodying a third form of the invention,

Figure 12 is a plan view of the same,

Figure 13 is an exploded perspective view of the brush holder.

In the drawings, where for the purpose of illustration are shown preferred embodiments of our invention, attention being called first to Figures 1 to 5 inclusive, the numeral 10 design-

2

nates generally a centrifugal switch of the type disclosed in our co-pending application, Serial Number 123,880, filed October 27, 1949. The switch 10 includes a disc or carrier 11 formed of electrical insulating material and having end extensions or shoulders 12, upon which are mounted annular brush plates or slip rings 13 and 14.

Freely slidably mounted between the inner 10 and outer annular flanges 15 and 16 of the slip rings 13 and 14, are flat, thin plate brushes 17, formed of carbon, metal or the like. These plate brushes may be circumferentially elongated and arcuate, as shown, and have their inner flat faces slidably contacting the outer faces of the slip rings 13 and 14.

We have provided novel and simplified means for holding the plate brushes 17 in place. This means comprises an upstanding metal rod 18 to be connected at its lower end with a stationary part of the motor. The upper portion of this rod is screw threaded as shown at 19. Mounted upon the screw threaded portion 19 of the rod is an insulating sleeve 20, and insulating washers 21 and 22 are mounted upon the screw threaded portion 19 above and below the sleeve 20. The screw threaded portion 19 carries a lower nut 23 and an upper nut 24 and a lock nut 25. The washers 21 have notches 26 formed therein. The sleeve 20 has a flat 27 and carries an insulating washer 28.

Torsional coil springs 29 and 30 are mounted upon the sleeve 20 between the insulating washers 21 and 28, and are insulated from each other; corresponding outer ends of the coil springs are bent to provide radial extensions 31, Figure 5, held within a longitudinal groove 32 formed in the sleeve 20. The inner ends of the springs 29 and 30 are continued in the form of resilient arms 33, having extensions 34, provided with ends 35, bent at right angles thereto. These ends 35 are inserted within openings 36 formed in the plate brushes 17. The springs 29 and 30 serve to hold the plate brushes 17 in place and yieldingly press the same into engagement with the faces of the slip rings 13 and 14. The springs are in electrical connection with the slip rings.

Metal strips or tabs 37 are inserted within the outer ends of the springs 29 and 30, and engage the flat 27, and are in electrical contact with the springs. The tabs 37 have lateral extensions 38, held within the notches 26, Figure 4. The outer ends of these lateral extensions are bent into loops 39, as shown. Insulated wires 40 are permanently electrically connected with

the plate brushes 17 and the outer ends of these wires 40 are inserted within the loops 39. The ends of lead wires 41 are also inserted in these loops and the loops are pinched upon the wires to form a firm electrical engagement.

In use, the rod 18 is substantially vertically arranged and is supported in position by a bolt or the like passing through an eye 18' and secured to a fixed support separate from the centrifugal switch. The arms 34 hold the plate 10 brushes 17 in place in contact with the slip rings 13 and 14, in conjunction with the flanges 15 and 16 and the tortional coil springs 29 and 30 retain the plate brushes 17 in firm contact with the slip rings. The holder is mounted independently of the rotary switch, and dispenses with numerous elements ordinarily used to retain the brushes in place, when used in connection with the rotary switch including a rotary housing and rotary element therein. The plate 20 brushes 17 are uncovered and readily accessible and the construction is such that they may be easily removed and replaced. All parts of the holder may be readily assembled.

In Figures 6 to 10 inclusive, we have shown a 25 second modification of the invention. The same centrifugally operated switch 10 is used, having the slip rings 13 and 14 coacting with the plate brushes 17 which may be formed of carbon, metal or the like.

The brush holder comprises a stiff rod or wire 42, provided at its lower end with an eye 43 for attachment to a stationary part of the motor separate from the switch. Arranged at the upper end of the rod 42 is a cylindrical supporting member 44, provided at its lower end with a longitudinal opening 45 to receive the rod. This supporting member is formed of insulating material and has a transverse opening 46 to receive a drop of solder 47 to be anchored to the rod 42. Other means may be employed to rigidly secure the insulating supporting member to the rod 42. The insulating supporting member 44 is provided with upper and lower diametrically extending openings 48 and 49, as shown.

Mounted upon the supporting member 44 are tortional upper and lower coil springs 50 and 51, separated by an insulating washer 52, mounted upon the supporting member 44. The outer ends of the springs 50 and 51 have radial extensions 53, which are anchored within recesses 54, as shown. The inner ends of the springs 50 and 51 are continued in the form of arms 55, bent to provide heads 56, having transverse extensions 57 to engage within openings 58 formed in the plate brushes 17.

An upper lead wire 59 extends through the opening 48 and is thereby attached to the supporting member 44, and the free end of this wire if stripped of insulating material and is electrically connected with the coil spring 50 by solder or the like, as indicated at 60. This point of attachment is near the extension 53. A lower lead wire 61 extends through the opening 49 and is thereby attached to the insulating supporting member 44 and its free stripped end is electrically connected with the coil spring 51 by solder 62.

It is thus seen that the springs 50 and 51 hold the plate brushes 17 in firm sliding engagement with the slip rings, and that the current is supplied to the plate brushes through the springs 50 and 51.

In Figures 11, 12 and 13, we have shown a third modification of the invention, including a cylindrical insulating supporting member 63, having a

longitudinal screw-threaded opening 64 at its lower end to receive the screw-threaded end of a vertical rod 65, carrying a lock nut 66. This rod is provided with an eye 67 for attachment with a stationary part of the motor separate from the switch. The same springs 50 and 51 are mounted upon the supporting member 63, and have their upper and lower ends anchored to the supporting member by the extensions 53 engaging in the recesses 54 and the same insulating washer 52 is provided. The springs 50 and 51 have the same arms 55 and heads 56, carrying the pins 57, engaging with openings formed in the plate brushes 17.

In this form of the invention, the current is not supplied through the springs 50 and 51, and we use metallic connector strips 68, bent to provide U-shaped ends 69 and 70. The U-shaped ends 69 receive the heads 56 and are provided with openings 71, to receive the pins 57. The heads 56 may be soldered to the U-shaped ends 69. Lead wires 72 extend into the U-shaped ends 70 and may be clamped therein or secured thereto by solder. The same switch 10 is used.

In use, the current passes through the connector strips 68 to the plate brushes 17 and not through the springs 50 and 51.

It is to be understood that the forms of our invention herewith shown and described are to be taken as preferred examples of the same and that various changes in the shape, size and arrangement of parts may be resorted to, without departing from the spirit of our invention or the scope of the subjoined claims.

Having thus described our invention, we claim:

1. A holder comprising a supporting element, an insulating sleeve mounted upon the supporting element and provided between its ends with an insulating flange, said sleeve having a flat and a groove formed upon its face, coil springs mounted upon the sleeve upon opposite sides of the flange and having corresponding ends bent to provide lateral extensions held within the groove, tabs arranged upon the flat and disposed inwardly of the coil springs, means for connecting lead wires with the tabs, arms carried by the opposite ends of the coil springs, and brush contacts carried by the arms, and wires connecting the tabs and brush contacts.

2. A holder comprising an insulating supporting member, a supporting element carrying the insulating supporting member, tortional coil springs carried by the insulating supporting member and insulated from each other and having corresponding ends anchored to the insulating supporting member, arms carried by the coil springs, the coil springs serving to conduct current, brush elements carried by the arms, and wires secured to the insulating supporting member and connected with the coil springs.

3. A holder comprising an insulating supporting member having openings formed therein, an element to support the insulating supporting member, tortional coil springs carried by the insulating supporting member and insulated from each other and having their ends anchored to the insulating supporting member, arms carried by the coil springs, the coil springs and arms serving to conduct current, brush elements carried by the arms, and wires held within said openings and electrically connected with the coil springs.

4. A holder comprising an insulating supporting member, an element supporting said member, tortional coil springs carried by the insulating supporting member and insulated from each

other and having their ends anchored to the insulating supporting member, arms carried by the coil springs, brush elements carried by the arms, and conductors electrically connected with said arms.

5. A holder comprising an insulating supporting member, an element to support said member, torsional coil springs carried by the insulating supporting member and insulated from each other and having ends anchored to the insulating supporting member, arms carried by the coil springs provided with transverse pins, brush elements having openings to receive the pins, electrical conductor strips provided with substantially U-shaped ends including sides having openings, said arms extending into the substantially U-shaped ends and the pins extending through the openings in the sides of such ends.

6. A switch device comprising, a rotary disc, slip rings mounted upon the opposite sides of the 20 rotary disc and having annular flanges, a supporting element separate from the disc, a gen-

erally cylindrical insulating member mounted upon the supporting element and provided in its periphery with recess means, coil springs mounted upon said insulating member and provided at its ends with lateral extensions to enter the recess means, arms carried by the opposite ends of the coil springs and crossing each other and having laterally extending pins, and plate brushes engaging the slip rings and having openings to receive the pins.
